[57] CLAIM

The ornamental design for a body surfing board, as shown and described.

DESCRIPTION

FIG. 1 is a front and left side perspective view of a body surfing board showing my new design;

FIG. 2 is a front elevational view thereof;

FIG. 3 is a left side elevational view thereof, the right side elevational view being a mirror image of that shown;

FIG. 4 is a top plan view thereof;

FIG. 5 is a rear elevational view thereof;

FIG. 6 is a bottom plan view thereof;

FIG. 7 is a rear elevational view of a second embodiment of the body surfing board, the sides, bottom and front view of the second embodiment being identical to the first embodiment with the exception of the straps; and,

FIG. 8 is a front and left side perspective view of FIG. 7.

The portions of FIGS. 1 and 8 shown in broken lines represent users of the two embodiments in the environment of use and form no part of the claimed design.
